UNITED STATES PATENT OFFICE.

EMIL TAVASTILA, OF DONORA, PENNSYLVANIA.

AUTOMATIC SHUT-OFF FOR GAS-BURNERS.

No. 856,742.

Specification of Letters Patent.

Patented June 11, 1907.

Application filed January 23, 1907. Serial No. 353,715.

To all whom it may concern:

Be it known that I, EMIL TAVASTILA, a citizen of the United States of America, residing at Donora, in the county of Washington and State of Pennsylvania, have invented certain new and useful Improvements in Automatic Shut-Offs for Gas-Burners, of which the following is a specification, reference being had therein to the accompanying drawing.

This invention relates to automatic shut offs for gas burners, and the invention has for its object to provide a novel shut off wherein positive and reliable means are employed for automatically closing a valve that controls the supply of gas to a burner.

Another object of this invention is to provide a novel shut off that can be used in connection with a burner of a stove and lamp whereby should the supply of gas be shut off unbeknown to the occupants of a room or compartment in which the burner is located, my improved shut off will be immediately actuated to close a valve and prevent the escape of gas into the compartment or room, thus preventing the occupants thereof from being asphyxiated.

With the above and other objects in view, which will more readily appear as the invention is better understood, the same consists in the novel construction, combination and arrangement of parts to be hereinafter more fully described and then specifically pointed out in the appended claims.

Referring to the drawing forming part of this specification, like numerals of reference designate corresponding parts throughout the several views, in which:

Figure 1 is a perspective view of a portion of a stove and burner equipped with my improved shut-off, Fig. 2 is an elevation of a portion of the shut off, Fig. 3 is a plan of the same, Fig. 4 is an elevation of the shut off designed for a lamp fixture, Fig. 5 is a vertical sectional view of a portion of the same, and Fig. 6 is a perspective view of a portion of the shut off as designed for a lamp fixture.

In the accompanying drawing, I have illustrated a stove 1 of a conventional form, the stove being provided with a cylindrical perforated burner 2 having an air mixer 3 and a gas supply pipe 4. Above the burner 2 is arranged an asbestos backing or deflector plate 5.

My invention resides in interposing a valve casing 6 upon the gas supply pipe 4, said valve casing having an elongated valve stem 7. The upper end of the valve stem 7 is provided with a thumb piece 8 and with an outwardly extending indicator arm 9, carrying a fan-tail shaped signal plate 10. The stem is also provided with an outwardly extending finger 11. Revolvably mounted upon the stem 7 and upon the valve casing 6 is a collar 12 having a notch 14 formed therein.

The valve casing 6 supports an integral tubular extension 15 and connecting with said extension is a coiled spring 16 which passes around the collar 12 and is secured to said collar as at 17. The spring 16 is employed for normally holding the collar in a fixed position.

The gas supply pipe 4 beneath the valve casing 6 is provided with a T connection 18, which supports a bracket 19, said bracket being located within the stove 1 beneath the burner 2. The bracket carries an upwardly extending arm 20 and to the upper end of said arm is adjustably connected a strip of non-fusible metal 21 capable of expanding and contracting. The opposite end of the strip 21 is provided with a permanent sleeve 22 carrying a depending arm 23 to which is pivotally connected a washer 24. The washer 24 is provided with an upwardly extending lug 25 and extending through said washer into the sleeves 15 and 22 is a slidable rod 26. A coiled spring 27 is loosely mounted upon the rod 26 and between the sleeve 22 and the washer 24 to normally hold the washer against inward pivotal movement and loosely upon the rod 26. A coil spring shown in dotted lines is placed within the sleeve 22 and behind said rod 26, normally forcing the rod outward and into engagement with the collar 12.

By said means as described, it will be readily understood that said rod 26 will have free and assistant movement in an outward direction toward the collar 12, being so impelled by the hidden spring 100 within the sleeve 22 and also by the expansion of the strip 21. It is pointed out, however, that in contracting, the strip 21 will draw inwardly the sleeve 22 and arm 23. By this movement the pivoted washer 24 will be 105 tilted outward thus gripping the encircled rod 26 and carrying the latter inward and out of engagement with the collar 12. In

order that there may be a co-operation between the collar 12 and the valve stem 7, I provide said collar with an upwardly extending pin 28 adapted to be engaged by the finger 11.

The operation of my improved automatic shut-off in connection with the gas burner of a stove is as follows: The valve stem 7 is rotated until the lug 11 engages the pin 28 and 10 revolves the collar 12. As the collar 12 is revolved upon the valve casing 6, the coiled spring 16 is placed under tension and is retained under tension by the end of the rod 26 engaging the notch 14 of the collar 12 through 15 the agency of the hidden spring within the sleeve 22. The valve stem is then turned rearwardly until the indicator arm 9 is at right angles to the gas supply inlet nipple 29, this position of the arm and signal plate 10 indicating that the valve is open and that 20 gas is passing into the burner 2. Upon the gas being ignited, the strip of metal 21 expands and further tends to hold the rod 26 in engagement with the collar 12. Should the 25 gas supply be shut off unbeknown to the occupants of the compartment in which the gas stove is located, the cooling of the strip of metal 21 will cause the same to contract and withdraw the pin 26 from the notch 14 of the 30 collar 12. The coiled spring 16 which has been under tension revolves the collar 12 causing the pin 28 to engage the finger 11 and turn the valve stem 7, closing the gas supply pipe and preventing gas from entering the 35 burner, the closing of the valve being indicated by the change in position of the signal plate 10. Upon again revolving the valve stem 7 to turn on the gas the plate 10 will be brought forcibly in contact with the lug 25 40 upon the washer 24, thus tripping the latter out of its temporary engagement with the encircled rod 26 and allowing said rod to move outward to engage the collar 12, under the influence of the hidden spring within the 45 sleeve 22.

In Figs. 4 to 6 inclusive, I have illustrated the application of my improved automatic shut off, to a lamp fixture. The gas supply pipe 30 is provided with a valve 31 having a 50 valve stem 32, the lower end of which is provided with a thumb piece 33 while the upper end of said stem is provided with a beveled segment-shaped lug 34. A coiled spring 35 is mounted upon the valve stem 32 beneath 55 the valve 31, to normally hold the stem 32 in its seat. The valve stem 32 is provided with a finger 36 for engaging the upwardly extending pin 37, carried by a collar 38 revolubly mounted upon the stem 32 and valve 31. 60 Connecting with the collar 38 is a coiled spring 39, which is connected to the lamp fixture as at 40. The collar 38 is notched as at 41, similar to the collar 12 previously described. The gas supply pipe 30 is provided 65 with an upwardly extending bracket 42

overhanging the globe and mantle of the lamp fixture. The lamp fixture beneath the burner is provided with a bracket 43 supporting a vertically disposed sleeve 44 into which a rod 45 is slidably mounted. The rod 45 being also slidably mounted within a sleeve 46, and said sleeve permanently secured to a strip of metal 47 which in turn is adjustably connected as at 48 to the upper end of the bracket 42. The strip of metal 47 has the properties of expansion and contraction. The sleeve 46 is provided with a depending arm 49 carrying a pivoted washer 50 similar to the washer 24 previously described. Interposed between the washer 50 and the lower end of the sleeve 46 is a loosely mounted coiled spring 51 for normally holding the washer in a horizontal position. The end of the rod 45 is adapted to engage in the notch 41 of the collar 38, 85 when the same is rotated by the finger 36 of the valve stem 32 engaging the pin 37 of the collar 38. When the strip of metal 47 contracts by the gas supply being shut off, the rod 45 is adapted to release the collar 38 and 90 the spring 39 of said collar to rotate the valve stem 32 to close the valve 31. The function and operation of the remaining parts is identical to that of corresponding parts heretofore fully described in connection with my improvement as applied to a stove. It will be noted however, that the beveled segment-shaped lug 34 is employed for tripping the washer 50 out of its temporary engagement with the rod 45. This being accomplished automatically by said lug being forcibly brought beneath and elevating said washer upon manually revolving the valve stem 32 to turn on the gas. In this manner the escape of gas will be prevented 105 when the supply is shut off unbeknown to the owners of the lamp fixture.

From the foregoing it will be observed that I have devised a novel shut off for gas burners which is automatic and positive in 110 its action. I do not care to confine myself to the specific arrangement of the various parts of my improved shut off or to its application entirely to a stove or lamp fixture.

Such changes in the size, and minor details of construction as are permissible by the appended claims, may be resorted to without departing from the spirit and scope of the invention.

What I claim and desire to secure by Letters Patent, is:—

1. In an automatic shut off the combination with a gas supply pipe and burner, of a valve controlling the supply of gas to said burner, a valve stem for operating said valve, 125 a spring held collar mounted upon said valve for moving said stem and a strip of metal arranged in close proximity to said burner, sleeves mounted upon said strip of metal and said valve and a slidably spring-pressed rod 130

carried partially within said sleeves, a projecting end of said rod adapted to engage a notch in the periphery of said collar, a pivoted washer encircling said rod and adapted to engage the latter during movement in only one direction, said strip of metal being expanded and contracted by the action of said burner.

2. An automatic shut off consisting of a valve, a valve stem for operating said valve, a spring held collar revolvably mounted upon said valve for operating said stem, and a slideable spring-pressed rod in engagement with

an expandible metallic strip and adapted to engage said collar for normally holding the latter in a fixed position, a pivoted washer encircling said rod and adapted to temporarily engage the rod and a lug mounted upon the valve stem for tripping the washer out of engagement with said rod.

In testimony whereof I affix my signature in the presence of two witnesses.

EMIL TAVASTILA.
